UNITED STATES PATENT OFFICE.

CHARLES D. MOSHER, OF NEW YORK, N. Y., ASSIGNOR, BY MESNE ASSIGNMENTS, TO THE BABCOCK & WILCOX COMPANY, OF BAYONNE, NEW JERSEY, A CORPORATION OF NEW JERSEY.

STEAM-BOILER.

1,150,951.

Specification of Letters Patent. Patented Aug. 24, 1915.

Application filed January 31, 1912. Serial No. 674,626.

To all whom it may concern:

Be it known that I, CHARLES D. MOSHER, a citizen of the United States, residing in the borough of Manhattan of the city of 5 New York, in the State of New York, have invented certain new and useful Improvements in Steam-Boilers, of which the following is a specification, reference being had to the accompanying drawings, which 10 form a part hereof.

The object of this invention is to provide highly efficient means for heating the air which is to be supplied to the fire-box of a steam boiler for the purpose of 15 supporting and promoting combustion therein, the heat being derived from the products of combustion after the absorption of heat therefrom by the water in the boiler.

The invention is realized most advantageously in connection with water tube boilers 20 which comprise a steam drum, one or more water drums, and water tubes which connect the steam drum with the water drum or with the water tubes and will be explained hereinafter with reference to its 25 embodiment in a boiler of the general class referred to, although it is capable of a wider application.

In the accompanying drawings in which 30 the invention is illustrated—Figure 1 is a view partly in front elevation and partly in transverse section, on opposite sides of a median line, of a water tube boiler to which the invention is applied. Fig. 2 is a partial 35 view of the same in horizontal section. Fig. 3 is a view of the same partly in side elevation and partly in longitudinal section. Fig. 4 is a partial view of the same in horizontal section below the water drum. Fig. 40 5 is a detail view in perspective illustrating a possible detail of construction.

The boiler shown in the drawings comprises a casing *a*, a steam drum *b*, two water drums *c* and water tubes *d* which connect 45 the steam drum with the water drums. The boiler may be heated by gaseous, liquid or solid fuel but is shown as adapted to be heated by solid fuel, as indicated by the grate *e*, below and above which are formed 50 the ash pit *f* and the combustion chamber *g*. Above the water tubes *d* and between the same and the casing *a* is the usual gas space or uptake *h* through which the products of combustion, after they pass between 55 the water tubes and give up to them as

much as possible of their heat, pass on their way to the stack *i*, a grid damper *k* being interposed in the uptake and provided with the usual openings *k'* for the purpose of regulating the flow of the heated gases. All 60 of these parts are shown as arranged as usual in boilers of the class referred to, but may be arranged in any suitable manner.

In the development of this invention regard has been had to the known difficulty 65 of heating considerable volumes of air, whether stationary or moving, within which there is no internal circulation, it being well known that air and other inert gases are effective non-conductors and are 70 self-insulating, that is to say, that while the temperature of the outer sheath or layers of a body of air may suffer change in temperature through immediate contact with a body of different temperature, such outer 75 sheath or layers insulate the inner body of the volume, which does not suffer material change in temperature except by the slow process of convection, unless internal circulation is established so as to bring every 80 particle of air in contact with the body of different temperature. This is true of air in motion either through a tube or around it, the sheath or layer of air next the tube alone becoming cooled or heated as the case 85 may be and acting as an insulating layer as to other portions. For this reason the tubular air heaters heretofore employed have a low efficiency and require a very 90 large area of heating surface to produce 90 substantial results. Furthermore the air heaters which are made up of tubes, especially when the tubes are in a horizontal position, quickly lose a large portion of their original efficiency through the settlement of soot on the upper sides of the tubes, which effectively insulates about one-third 95 of the available heating surface of each tube.

By the present invention the objections to 100 the use of tubular air heaters are overcome by the formation, in the uptake *h* or wherever else the hot gases are available after they have given up heat to the generator, of alternating passages *h'* for the hot gases 105 and relatively thin or narrow passages *l* for the air to be heated, the latter being adapted to receive at one end the air to be heated and to deliver it at the other end to suitable channels by which the heated air is con- 110

ducted to the furnace. Furthermore, the passages are corrugated or waved or sinuous so that the hot gases of combustion, being deflected back and forth in their passage, 5 impinge nearly at right angles upon the walls of the relatively thin air passages and thereby produce a maximum heating effect. The thickness of the air passages is preferably made as little as is consistent with the 10 supply of the required volume of air in order that the insulating effect of the sheath or outer layer of the air may be reduced as much as possible and the entire volume of air heated to as high a degree as possible.

15 The alternating passages for hot gases and air may be formed conveniently as represented in Fig. 5, in which the sheets τ of metal which form the walls of the passages are secured to end plates τ^2 .

20 It is well understood that uptake and gas passages which are sufficiently large to accommodate the waste gases when a boiler is being fired to a maximum degree, are too large when the boiler is being fired at a low 25 rate of combustion on account of the smaller volumes of gas evolved, and that in this latter condition the gases tend to short-circuit and fail to pass in contact with all of the tube surfaces, with a consequent loss of efficiency. The gas spaces or passages h' are therefore suitably spaced or distributed so as to cause a substantially equal distribution of the gases over all portions of the tube surface and each of such passages preferably 30 registers at its upper end with a corresponding aperture or line of apertures k' in the grid damper k so that, when the damper is adjusted for different rates of combustion the equal distribution of the gases will still be maintained. At their forward ends the air passages communicate with an air header m which is formed within the casing a of the boiler at the front and is provided with dampers m' by which the admission of air 35 may be regulated and controlled. At their rear ends the air chambers or conduits l communicate with an air header n which is formed between the rear wall a' of the casing and the rear wall a^2 of the combustion 40 chamber, such air header n communicating with the ash pit f and, it may be, through holes a^5 with the combustion chamber above the grate e . In the air header n may also be placed webs n' which extend from the 45 rear wall of the combustion chamber toward but not to the rear wall a' of the casing. These webs form a large radiation surface 50 for the heat of the rear wall of the furnace

and further heat the air which is guided and distributed by them on the way to the combustion chambers; and they also act as stays to keep the plate to which they are secured from warping. The air header n may also communicate with a lateral passage n^2 formed between the side wall a^3 of the casing and the side wall a^4 of the combustion chamber so as to supply air at the side of the combustion chamber through holes a^5 in the brick at the sides of the combustion chamber. 60

It will now be seen that the hot gases in the uptake, after they have given up to the water tubes a large proportion of their heat, impinge upon the walls of the air passages l and give up still more of their heat to the air which, in passing through these corrugated heaters, is itself made to impinge upon the heated walls. A constant supply of fresh air being admitted to the heaters through the front dampers m' and the front header n and a flow thereof being induced 70 through the action of the draft, highly heated air is constantly supplied by the heaters and is delivered to the ash pit below the grate or to the combustion chamber above the grate, being further heated and 75 distributed to various points by the webs n' .

It will be understood that the details of construction and arrangement may be varied to suit different boilers and different conditions of use and that the invention is not 80 limited to the particular construction and arrangement shown and described herein. 85

I claim as my invention:—

The combination with a boiler and casing, 90 of an integral air heater located in the uptake and composed of metal sheets secured to end plates so as to form between them in alternation passages communicating with the combustion chamber and the stack and passages through corresponding openings in 95 the end plates communicating with the atmosphere and the combustion chamber, heat radiating webs secured to the rear wall of the combustion chamber and disposed in the 100 passages between the air heater and the combustion chamber, the sheets being spaced to distribute equally the hot gases from the combustion chamber, and adjustable dampers 105 to control the flow of hot gases through the passages therefor.

This specification signed and witnessed 110 this 30th day of January A. D., 1912.

CHARLES D. MOSHER.
